Patented June 15, 1920.

FIG. 2.

FIG. 3.

John Spencer Johnston
Inventor

By *Geo. P. Kimmel*
Attorney

UNITED STATES PATENT OFFICE.

JOHN SPENCER JOHNSTON, OF ETIWANDA, CALIFORNIA.

WEDGE FASTENER FOR TOOL-HANDLES.

1,343,781.

Specification of Letters Patent. Patented June 15, 1920.

Application filed March 18, 1919. Serial No. 283,394.

To all whom it may concern:

Be it known that I, JOHN SPENCER JOHNSTON, a citizen of the United States, residing at Etiwanda, in the county of San Bernardino and State of California, have invented certain new and useful Improvements in Wedge Fasteners for Tool-Handles, of which the following is a specification.

10 This invention relates to devices adapted for securing wood members in other members, such as the handles of hammers, sledges, axes, and the like, and which may also be employed for securing wood members of other forms in metal members of various forms.

For the purpose of illustration the improved device is shown applied to an ordinary hammer head and its wood handle, and 20 has for one of its objects to provide a simply formed device which effectually prevents the handle from working loose, or becoming separated from the head or body in which it is inserted.

25 Other objects, as well as the nature, characteristic features and scope of this invention will be readily apparent from the following description taken in connection with the accompanying drawings and pointed 30 out in the claim, forming a part of this specification.

The invention is clearly illustrated in the accompanying drawings, in which,

Figure 1 is a side elevation showing the 35 device applied to a conventional hammer.

Fig. 2 is a vertical sectional view through the hammer head showing the device arranged between the head and the handle and in elevation,

40 Fig. 3 is a perspective detail of the fastener when detached, and

Fig. 4 is an elevation view of the same.

Similar characters of reference are employed in all of the above described views, 45 to indicate corresponding parts.

Referring now, more particularly, to the accompanying drawings there is illustrated a handle 1 which has mounted on one end thereof a tool head 2 in the present instance 50 in the form of a hammer while arranged between one face or side of the handle and the adjacent side of the opening through the head is the improved fastener designed to prevent accidental displacement of the 55 head from the handle.

The improved device formed from a single strip of resilient strap metal which is folded upon itself to provide juxtaposed portions 3 and 4, the portion 3 being shorter than the portion 4 and is formed on its upper end with a plurality of upwardly and outwardly inclined teeth 5 adapted for biting engagement with the handle when the device is arranged between the head and the handle. The other portion 4 terminates 60 in a laterally and outwardly extending and thickened retaining flange 6. This flange is preferably provided by rolling the terminal portion of the tool head engaging portion 4 upon itself and subsequently flattening the same as shown in Fig. 3.

At the junction of the portions 3 and 4 the strip is rounded to produce an enlargement, as shown at 7 in Figs. 2 and 3.

In applying the device in position on 75 either an old or a new handle the portion 4 is inserted in the opening in the tool head 2 with the flange 6 engaging the outer edge of the head and the enlargement extending over the inner edge of the opening 80 with the spurs or teeth 5 intermediate the opening. The handle 1 is then inserted in the opening in the tool head and forced into the opening to cause it to assume the position indicated in Figs. 1 and 2, one side of the 85 handle engaging the portion 3 while owing to the resiliency of the material and the snug fitting of the handle in the opening in the head the teeth 5 will bitingly engage the handle for anchoring the fastener to the 90 handle while the flange 6 and the enlargement 7 operates to retain the head against displacement. It is to be also observed that the intermediate enlarged portion 7 of the metal from which the fastener is formed is 95 positioned beyond the inner edge of the head and serves to coact with the flange in maintaining the head against movement in either direction.

It is believed in view of the foregoing description that a further detailed description of the operation of the invention is entirely unnecessary. Likewise, it is believed that the advantages of the invention will be readily apparent.

Still further embodiments of the invention than those herein especially defined may be resorted to as conditions or preference may dictate, as may be in keeping with the hereto appended claim.

Having thus fully described the invention what is claimed as new and desired to be secured by Letters Patent is:-

A holding device formed of a strip having a lateral offset at one end and laterally directed spurs at the other end and bent upon itself intermediate the ends with the material of the strip curved at the bend to form an enlargement, whereby when inserted in the handle receiving aperture of a

tool the lateral offset and the enlargement will bear over the body of the tool at the ends of the aperture and coact to prevent displacement of the handle when forced into the aperture in engagement with the holding device.

In testimony whereof, I affix my signature hereto.

JOHN SPENCER JOHNSTON.
